UNITED STATES PATENT OFFICE.

WILLIAM P. DRUMHELLER, OF SPRINGFIELD, MASSACHUSETTS, ASSIGNOR TO WILLIAM CARTER COMPANY, OF NEEDHAM HEIGHTS, MASSACHUSETTS, A CORPORATION OF MASSACHUSETTS.

MECHANISM FOR LUBRICATING THE NEEDLES AND NEEDLE CAM TRACKS OF KNITTING MACHINES.

Application filed November 13, 1922. Serial No. 600,589.

To all whom it may concern:

Be it known that I, WILLIAM P. DRUMHELLER, a citizen of the United States, and a resident of Springfield, in the county of 5 Hampden and State of Massachusetts, have invented an Improvement in Mechanism for Lubricating the Needles and Needle Cam Tracks of Knitting Machines, of which the following description, in connection with 10 the accompanying drawings, is a specification, like characters on the drawings representing like parts.

This invention relates to means or mechanism for lubricating the needles and needle 15 cam grooves or tracks of knitting machines and particularly to circular knitting machines of the dial type. In order that the principle of the invention may readily be understood I have disclosed a single embodiment thereof in the accompanying drawings, wherein:

Fig. 1 is a plan view of a part only of a circular dial knitting machine having my invention applied thereto;

Fig. 2 is a vertical section upon the line 2—2 of Fig. 1, and Figs. 3 and 4 are views similar to Figs. 1 and 2 respectively, but of a slightly modified form of my invention.

Attempts heretofore have been made to 30 supply lubricant and especially oil to parts of knitting machines but they have not been wholly satisfactory and have frequently resulted in the oil flowing to and soiling the infeeding yarn or the knitted fabric. I am 35 also aware that in the patent to Arnold 106,025 dated August 2, 1870, there is disclosed a straight knitting machine of the Lamb type wherein a reservoir for lubricating material was provided from which oil 40 was supplied to a sponge by means of capillary attraction through a wick extending from the reservoir. In such case the sponge was applied in such a way that the needles passed through the same. So far as 45 I am aware no mechanism embodying the disclosure of said Arnold patent is upon the market and the construction there disclosed is objectionable for many reasons, and particularly because the needles are compelled 50 to pass through the sponge material.

I have represented my invention as applied to a circular knitting machine and while my invention is not restricted in its

scope to the disclosed type of machine it is peculiarly applicable to a machine of the 55 circular type having a dial.

In the drawings I have represented parts of a circular knitting machine including the needle cylinder 1, the cam ring 2, the dial 3, and the dial cam plate 4. In suitable 60 grooves in the needle cylinder and the dial are provided needles 5, 6 which may be of any suitable type. In the disclosed machine the needle cylinder is rotated by means of a gear wheel 7 and the dial is 65 caused to rotate therewith. The disclosed machine is one adapted for knitting under- 70 wear and to that end is desirably provided with a relatively large number of cam sets in both the needle cylinder and the dial and to each pair of sets of cams yarn is fed in a manner which need not be particularly described. In Fig. 1 I have indicated in dotted lines at 8, 9, 10, 11 and 12 certain of the 75 cams of one of the sets and have indicated at 13 the groove through which the needle butts 14 travel, it being understood that the butts 15 of the cylinder needles 5 travel through a corresponding groove 16.

In accordance with my invention I provide at one or more points upon the machine a receptacle 17 for supplying the dial needles. Desirably said receptacle is secured by screw 18 or otherwise to the flat ring 19 surrounding the needle cylinder and receives a supply of oil 20 through the covered opening 21. From said receptacle leads a suitable pipe or other passage 22 extending to the dial cam plate 4, which is provided with an opening 23 to receive the same. Said pipe 22 is secured to the dial cam plate by any suitable means as, for example, by a small disk or plate 24 which is itself secured by a screw 25 to the dial cam plate 4. In the pipe 22 is a wicking 26 of 95 suitable material, which extends down to the bottom of the receptacle 17 and also extends throughout the length of said pipe 22 so that its end 27 actually engages the butts 14 of the needles as the same pass thereunder in the knitting operation.

While I might under certain circumstances and with certain positions of the receptacle 17 supply lubricant therefrom to the cylindrical needles 5, I preferably provide a second receptacle 28 which is secured 105

by screws 20 or otherwise to the under side of the annular member 19 so that the oil supply 29 is wholly beneath the cylinder needles 5.

5. Within the receptacle 28 I position a suitable wicking 30 and the same extends through a pipe 31 which itself passes through opening 32 in the annular member 19 and also through a suitable opening 33 in 10 the cam cylinder 2. The wick 30 as clearly shown in Fig. 2 extends to the point 34 where the butts 15 of the cylinder needles 5 touch the same in their rotation.

It will be observed that the lubricant reservoirs 17 and 28 are both wholly below the needles which are supplied therefrom so that the oil or other lubricant is supplied wholly by capillary action and in such limited quantities that no possible excess of material 20 would reach the yarn or the fabric.

Not only are the butts 14, 15 of the needles supplied with lubricant but through such supply to the needle butts the cam grooves themselves become properly oiled or lubricated.

In Figs. 3 and 4, I have illustrated the modification above referred to. In said figures, I have represented a receptacle 17' corresponding to the receptacle 17 of Figs. 1 30 and 2, but of enlarged capacity and located sufficiently low to provide for the supply of lubricant by wicks 26 or 30' to both sets of needles. It is unnecessary to describe in detail the structure shown in said figures. I 35 have, in said figures, in illustrating the novel features of the invention used the same numerals as in Figs. 1 and 2, but added a prime.

Having thus described one illustrative embodiment of my invention, I desire it to be understood that although specific terms are employed, they are used in a generic and descriptive sense and not for purposes of limitation, the scope of the invention being 45 set forth in the following claims.

Claims—

1. Knitting mechanism having independently movable needles provided with butts and means to supply lubricant to the said 50 needle butts, said means including a lubricant-carrying member in contact with said butts.

2. Knitting mechanism having independently movable needles provided with butts, and means functioning through capillary action to supply lubricant material to said 55 needle butts, said means including a lubricant-carrying member in contact with said butts.

60 3. Knitting mechanism having independently movable needles with butts, a carrier therefor, a plurality of oil receptacles supported independently of said carrier and located wholly lower than the said needles, and means for leading lubricant from said 65

receptacles directly to the vicinity of the butts of the said needles.

4. Knitting mechanism having independently movable needles, a carrier therefor, an oil reservoir located wholly lower than the path of the needles and supported independently of said carrier and wicking for leading the oil from said reservoir directly to the vicinity of the butts of said needles. 70

5. Oiling mechanism for the independently movable needles of knitting machines comprising a receptacle supported independently of the needle carrier and having means to position the same wholly lower than the path of the needles to be lubricated thereby, and wicking means for conveying the oil from said receptacle directly to the vicinity of the butts of said needles. 75 80

6. Knitting mechanism having independently operable needles provided with butts, an oil receptacle located below the path of said needles, a wicking tube extending from said receptacle through the cam carrying means for actuating the needles, and wicking positioned in said tube and adapted to 90 contact with the needle butts. 85

7. A circular knitting machine having a cylinder and a dial and independently operable needles in said cylinder and dial and two oil reservoirs for respectively conducting oil to the cylinder and the dial needles, each of said reservoirs being located wholly below the needles to be lubricated therefrom, and wicking means for conducting oil directly from each reservoir to the butts of 95 the needles pertaining thereto. 100

8. A circular knitting machine having a cylinder and a dial, and having a pair of oil reservoirs exterior to the needle cylinder, one of said reservoirs being mounted above and the other below the annular ring member surrounding the needle cylinder, the dial cam plate and the cam carrier for the cylinder needles each having an opening therein, tubes extending from said reservoirs and positioned in said openings, and wicking in 105 said tubes and extending therethrough and adapted to supply oil to the respective needle sets. 110

9. Knitting mechanism having independently movable needles with butts and also having operating cam means including a groove into which said butts project, and means to supply lubricant primarily and directly to said groove and thereby to the said 115 needle butts. 120

10. Knitting mechanism having independently movable needles with butts and also having operating cam means including a groove into which said butts project, a lubricant receptacle located wholly lower than 125 said needles, and means to supply lubricant in the first instance to the said groove whereby the needle butts in said groove receive the lubricant. 130

11. Knitting mechanism having independently movable needles with butts and a carrier therefor and also having operating cam means including a groove into which said butts project, and means including a lubricant container and a lubricant-carrying member at said groove structurally distinct from said needle carrier but extending from said container to supply lubricant from said 10 container to the needle butts in said groove.
12. Knitting mechanism having independently movable needles provided with butts and a carrier therefor, cam means for operating the needles and including a groove to 15 receive the needle butts, a lubricant receptacle and a pipe or passage structurally dis-
- tinct from said needle carrier but extending from said receptacle to the cam groove of the needle operating cam means, whereby lubricant is conveyed to the needle butts in 20 the cam groove.
13. Knitting mechanism having independently movable needles with butts, a carrier therefor, a lubricant receptacle supported independently of said carrier, and means 25 also supported independently of said carrier for leading lubricant from said receptacle directly to the vicinity of the butts of said needles.

In testimony whereof, I have signed my 30 name to this specification.

WILLIAM P. DRUMHELLER.
